UNITED STATES PATENT OFFICE

2,586,621

TWO-CYCLE INTERNAL-COMBUSTION ENGINE

Albin de Laage, Paris, France

Application February 27, 1948, Serial No. 11,572
In France May 20, 1946Section 1, Public Law 690, August 8, 1946
Patent expires May 20, 1966

3 Claims. (Cl. 123—74)

1

This invention relates to a two-cycle internal combustion engine. The essential characteristic of this engine resides in the fact that the compression chamber is formed by a movable sleeve which is disposed between the cylinder and the piston (in the manner of a four-cycle engine without valves). The movable sleeve is closed at its lower end and cooperates with the lower surface of the piston to cause pre-compression of the feed air and to act at the same time as a distributor for the compression chamber and the corresponding explosion chamber. Another feature of the invention which results from the closing of the lower end of the sleeve is that one or more of the connecting rods operate on the piston head from a lateral position.

In the schematic drawings annexed and which are given as examples only:

Figures 1, 2 and 3 illustrate the constituent parts of this engine in three different positions during the two movements occurring in the cycle;

Figure 4 is a sectional view of the engine taken at right angles to that shown in Figures 1, 2 and 3.

The two-cycle engine, which is the object of this invention, has in the usual manner an exhaust opening 1 and, at approximately the same height, an opposed inlet opening 2 which is connected through a lateral tube 3' with an opening 4 with the compressor. The opening and closing of these openings 2 and 4 are controlled by the relative positions of the piston 6 with respect to the corresponding cylinder 5.

In accordance with the invention, the compression chamber is formed by a movable sleeve 7 which is disposed between the bore of the engine cylinder 5 and its piston 6. This sleeve 7 is closed at its lower end by the bottom 8 of the compression cylinder 5 and its piston 6. This sleeve 7 is closed at its lower end by the bottom 8 and it thus forms, in combination with the lower surface of the piston 6, a compression pump. The sleeve 7 is also provided in its walls with a number of openings 9, 10, 11 and 12 corresponding to the openings 1, 2, 3 and 4 in the cylinder 5; these openings will provide, during the rectilinear movement of the sleeve 7 in opposite directions, a distributing system for the explosion chamber and the compression chamber. The sleeve 7 is controlled or driven by a connecting rod 13 which is connected to a handle 14 of the crank shaft 15.

Since the sleeve 7 is closed at its lower end, the piston axle 6 can no longer be driven by a connecting rod extending into the interior of the piston. The piston axle 16 therefore extends at one or both of its ends so as to pass through registering slots formed in the walls of the cylinder 5.

2
This invention relates to a two-cycle internal combustion engine. The essential characteristic of this engine resides in the fact that the compression chamber is formed by a movable sleeve which is disposed between the cylinder and the piston (in the manner of a four-cycle engine without valves). The movable sleeve is closed at its lower end and cooperates with the lower surface of the piston to cause pre-compression of the feed air and to act at the same time as a distributor for the compression chamber and the corresponding explosion chamber. Another feature of the invention which results from the closing of the lower end of the sleeve is that one or more of the connecting rods operate on the piston head from a lateral position.

The phases of the operation of this engine are the following, by reference to the figures of the schematic drawing attached:

15 Figure 1 shows the beginning of the expansion phase, after explosion, the piston having started on its downward travel; the corresponding crank handle 17 having passed its high dead point. The crank handle 14 which is moving the sleeve 7 downwardly is approaching its low dead point. All of the openings in the sleeve 7 are covered and the relative movement of the piston, being more rapid than the bottom 8 of the compression cylinder during this phase, results in the compression of gases that may be contained in the compression cylinder. In practical application, the piston will have two acting surfaces, so that it will have a flat face on the compressor side as well as on the expansion or driving side.

20 Figure 2 shows the end of the expansion phase and the beginning of the exhaust phase. The opening 9 in sleeve 7 unmasks the exhaust opening 1 for the burnt gases, then after this the two openings 2 and 4 of the tube 3' connecting the compressor chamber with the explosion chamber but the piston has not yet attained its low dead point so that the opening 2 of tube 3' is still closed by the latter. The opening 2 is unmaked by the movement of the piston 6 for the admission of the gas mixture to the explosion chamber, then the sleeve 7, having restarted its upward movement, will close the exhaust opening 1 to thus avoid the loss of a certain amount of fresh gas by seepage.

25 Figure 3 shows the start of the following stage. The piston 6 starts to rise again while the sleeve 7 ends its upward travel. The space between the

30 piston 6 and the sleeve 7 is filled with fresh gas.

piston 6 and the bottom 8 of the sleeve 1 will increase while the following happens: The sleeve 7 unmasks the inlet opening 3 while closing the lower opening 4 of the communicating tube 3'. The exhaust opening 1 of the explosion chamber is screened by the sleeve 1, and the piston 6 in rising will close the upper opening 2 of the tube 3'. The compressor will suck in a volume of fresh gas which it will then push into the explosion chamber as a result of or during the following cycle.

One may note that as a result of the opposite movements of the piston head 6 and the sleeve 1, it is possible to have, for the compressor, a cylindrical volume that is larger than the cylindrical volume of the explosion cylinder which assures a complete replenishment. As can be noted from the drawing, the connecting rod 13 is eccentrically connected to the movable sleeve in a manner to lengthen the fresh gas intake period and to shorten the compressor discharge period, thus assuring adequate intake and accelerating the transfer of the fresh gas into the explosion chamber. By this arrangement, the engine thus acts as an actual charging pump but this last, which has no valve, is unusual due to the fact that it is formed in the engine cylinder itself.

What I claim is:

1. In a two-cycle internal combustion engine comprising a cylinder, a piston, a movable sleeve between the piston and the cylinder, openings in said cylinder for the intake and exhaust and to receive a passage connecting the upper and lower portions of the cylinder, openings in said sleeve arranged to expose the proper cylinder opening in the desired sequence in accordance with the movement of the piston and sleeve, and an engine shaft, the improvement which comprises a closure entirely sealing the lower end of said mov-

able sleeve, a driving connection extending from said closure to the engine shaft for imparting up and down movement to said sleeve, vertical registering slots in the concentric walls of the cylinder and sleeve, a rod connected to the piston and passing through said registering slots, and a driving connection located outside of said cylinder and extending from the protruding portion of said rod to the engine shaft.

10 2. The improvement in two-cycle combustion engines as claimed in claim 1, in which a plurality of vertical registering slots, rods and outside driving connections are provided.

15 3. The improvement in two-cycle combustion engines as claimed in claim 1, in which the driving connection for the sleeve closure is connected eccentrically thereto so as to prolong the time of the sleeve's downward movement and diminish the time of the sleeve's upward movement.
